UNITED STATES PATENT OFFICE.

JOHN QUIST, OF DETROIT, MICHIGAN.

FIRE KINDLER.

Application filed October 8, 1921. Serial No. 506,275.

To all whom it may concern:

Be it known that I, JOHN QUIST, a citizen of Sweden, and a resident of Detroit, in the county of Wayne and State of Michigan, have invented certain new and useful improvements in Fire Kindlers, of which the following is a specification.

This invention relates to a device for starting fires in stoves or furnaces where 10 coal or other solid fuel is employed for heating.

The object of the invention is to provide a device of the above character adapted to be applied beneath the fire grates of a range, 15 stove or furnace for rapidly starting a fire.

It is also an object of the invention that the device be adapted to be permanently installed in the ash receiver or of a stove or furnace, or only inserted in the ash receiver or box during the starting of a fire if desired.

It is a further object of the invention that the device be economical and safe in operation.

25 Other objects, and objects relating to details of construction, combination and arrangement of parts will hereinafter appear in the detail description to follow.

The invention is illustrated by way of example in the accompanying drawings, in which:—

Figure 1 is a perspective view of a cook stove and illustrating the application of the invention,

35 Figure 2 is a perspective view of the fire starter when removed from the stove, with parts broken away to more clearly illustrate the invention,

Figure 3 is a vertical transverse sectional view of one of the containers of the device,

40 Figure 4 is a perspective view of a heating stove and showing a modified form of the invention applied,

45 Figure 5 is a front elevation of the fire starter shown in Fig. 4 and showing the bottom of the associated ash receiver of the stove in section, and

50 Figure 6 is a perspective view of another form of applying to the invention an ash box in the ash pit of a stove.

Referring to the drawings in detail and particularly to Figures 1 to 3 inclusive 10 indicates generally a cooking range or stove in which coal or other solid fuel is employed for heating. In the end 11 of the stove the fire box or grate is located. The stove has

the usual draft regulating means namely, the damper in the pipe as at 13, the slide 12 and the slide 15 of the door 14 which closes the front of ash pit in which is the usual 60 ash box or receiver 16.

In carrying out the invention there is provided a pair of containers 17 which are rectangular in shape and adapted to be placed longitudinally within the ash box 16. 65 The box 16 is provided with a pair of notches 18 at each end and from the rear end of each container 17 there extends a pin not shown which is journaled in the associated notch 18. From the front end of 70 each container there extends a crank 20 which is likewise in the end wall of the ash box, and thus pivotally supporting the containers. The containers are pivoted off center as shown in Figure 2 for the purpose of increasing the space between the sides of the containers when inverted and thus providing space through which ashes 75 may fall into pit. Each crank is provided with a handle 21 and upon the forward face 80 of the ash box 16 there is secured a pair of L-shaped rests 22 for each crank.

Within each container there is arranged a multiplicity of sheets of asbestos 23 which are divided into a plurality of units by the 85 sheets 24 which are preferably of iron. The sheets of iron and asbestos are arranged longitudinally of the containers to entirely fill the same but are slightly less in length as shown. The two iron sheets 90 25 are extended above the remainder of the sheets and the adjacent two sheets of asbestos 25' on each side thereof are likewise extended. These extended portions of the asbestos sheets 25' in each instance form a 95 wick. Each wick is supported on each side by the projections 27 formed at the upper edges of the adjacent iron sheets 24.

The top of each container is covered with wire screen of relatively large mesh in 100 order to protect the contents therein from rough wear.

In the operation of the present device when it is desired to start a fire in the stove, the fire box is first supplied with fuel, then 105 the containers 17 are filled with a suitable oil to the amount which the asbestos therein will absorb. The asbestos sheets 23 are porous and serve as a wick. The ash box during this operation is preferably partly 110 withdrawn as shown in Figure 1 and now may be returned to its proper position and

a light applied to the extended sheets 25. The flame will run the length of these extended portions of the asbestos sheets and also travel down between the projections 27 of the adjacent sheets 24 and thus quickly spread the flame over the entire top of each container. The sheets 24 will conduct the heat toward the bottom of the containers and thus heat the oil held in the asbestos sheets and in this manner aid in vaporizing the oil and facilitating combustion thereof. During this procedure the damper of the stove may be manipulated to produce the best results and thus the fuel within the fire box of the stove may become fully ignited.

After the fuel is properly ignited and the oil has been used in the containers the same may be turned over as shown in Figure 2. The space between the containers is sufficient to permit the ashes from the fire box to fall into the ash box or receiver 16 and by turning the containers over the asbestos is protected from falling ashes. Referring to Figures 4 and 5, 28 indicates generally a small heating stove of common design and construction which employs a box-like base 29 as an ash pit. In this instance I provide a removable lighter consisting of a pan 30 which is supported by a pair of runners 31 which extend from a point near the forward end thereof to the rear end as shown. Runners 31 rest on ash pit bottom and permit the runnerless portion of pan 30 to glide over door sill and stand level when pulled out for filling. The pan 30 is provided with a handle 32 and within the same there is suitably supported a lighter unit 33 which is a duplicate of either of the lighter units previously described and may be used with or without the ash box 30.

The operation of this form of lighter is substantially the same as the lighter units illustrated by the Figs. 1 to 3 inclusive and previously described with the exception that the pan 30 and lighter therein must be removed and emptied by hand when cold.

Referring to Figure 6, 34 indicates generally an ash box and 35 a lighter frame. The frame is bottomless and extends transversely of the ash box as shown; and is supported therein by a pair of runners as at 36, a runner being secured to each end of the frame. The frame may be provided with notches 37 in each of its ends for pivoting a pair of lighter units as shown in Figure 2 and heretofore described; also suitable L-shaped stops 38 may be secured upon each end of the frame to serve the same purpose as the members 22 in Figure 2. The operation of this form of the invention would be the same; and a handle 39 is secured to the frame 35 to facilitate the removing thereof.

I claim:

1. A lighter unit of the character described, comprising a receptacle, a plurality of upstanding sheets within said receptacle, said sheets being made of liquid absorbing material, and some of said sheets extending above the others for the purpose described. 70

2. A lighter unit of the character described, comprising a container, a plurality of upstanding sheets of asbestos arranged in said container to fill the same, and a plurality of heat conducting sheets interposed between the asbestos sheets. 75

3. A lighter unit of the character described comprising a container, a plurality of upstanding sheets of asbestos arranged in said container to fill the container, a plurality of heat conducting sheets interposed between the asbestos sheets, and a mesh wire 80 covering the top of said container.

4. A lighter unit of the character described comprising a container, a plurality of sheets of asbestos arranged in said container in vertical relation thereto, a plurality of heat conducting sheets interposed between the asbestos sheets, and a plurality of asbestos sheets extended above the remainder to form wicks. 90

5. A lighter unit of the character described comprising a container, a plurality of sheets of asbestos arranged in said container in vertical relation thereto, a plurality of heat conducting sheets interposed between the asbestos sheets at regular intervals, a plurality of the asbestos sheets being extended above the remainder to form wicks, and means for supporting said wicks. 100

6. A lighter unit of the character described comprising a container, a plurality of sheets of asbestos arranged in said container in vertical relation thereto, a plurality of heat conducting sheets interposed between the asbestos sheets at regular intervals, a plurality of the asbestos sheets being extended above the remainder to form wicks, and the conductor sheets adjacent the wicks likewise extended to support the wicks. 105

7. A lighter unit of the character described, comprising a container, a plurality of sheets of asbestos arranged in said container in vertical relation thereto, a plurality of heat conducting sheets interposed between the asbestos sheets, and a plurality of the asbestos sheets being extended above the remainder to form wicks, and portions of the conductor sheets adjacent the wicks likewise extended as set forth. 115

8. A lighter unit of the character described, comprising in combination, a container, a plurality of sheets arranged in upstanding relation in said container, said sheets being adapted to absorb liquid and some of said sheets extending above the 120

130

others to provide wicks, and a plurality of heat conducting sheets interposed between the liquid absorbing sheets for the purpose described.

5 9. In combination with an ash box a lighter unit, comprising a container, a liquid fuel absorbing means therein, and means for pivotally supporting said lighting unit in said container so that the same
10 may be inverted when not in use.

10. In combination with an ash box, a

lighter unit, comprising a pair of containers having a liquid fuel absorbing means therein, means for pivotally supporting one of said containers longitudinally and off center thereby increasing the space between the containers when both are inverted for the purpose specified. 15

JOHN QUIST.
